BANDAGE

Margaret S. Whinery, Anthony, Kans.

Application February 5, 1947, Serial No. 726,565

8 Claims. (Cl. 128—156)

1

This invention relates to improvements in bandages. More particularly, this invention relates to an improved nonslip surgical bandage that can be used to hold sterile dressings and gauze in position against the person of the user.

It is, therefore, an object of the present invention to provide an improved nonslip surgical bandage that can hold sterile dressings and gauze in position.

In the field of medicine, and particularly in the field of surgery, it is oftentimes necessary to make incisions in the skin and flesh of a patient or to close cuts or wounds in the skin and flesh of a patient. Where this is done it is desirable to apply sterile dressings or gauze to the wound, and then use some means to maintain the dressings and gauze in position. In some instances the dressings and gauze can be held in place by adhesive tape which is applied directly to the dressings or gauze and to the skin of the patient; but in many instances the use of adhesive tape is not desirable because the tape will adhere so tightly to the patient's skin that removal of the tape may cause such a movement or pulling of the skin and flesh being healed that the time of healing may be needlessly prolonged. Efforts have been made to avoid the use of adhesive tape for holding dressings or gauze in position and thus avoid the consequent retardation of the healing process; one of these efforts included the use of bandages that passed completely around the body of the user and pressed the sterile dressings or gauze against the incision or wound. Unfortunately many of the bandages proposed or used for this purpose have not been satisfactory; while they were free of the tendency to move or pull the skin and flesh of the patient they were subject to a pronounced tendency to slip or shift away from the sterile dressings or gauze and release the pressure thereon, thus permitting bleeding or facilitating the onset of infection. Either result is highly objectionable, and as a result bandages of this type are not satisfactory. The present invention obviates these objections by providing a nonslip surgical bandage that will not pull the skin of the user but will positively hold itself and the dressings or gauze in place, thus preventing needless bleeding and keeping dirt and foreign matter away from the incision or wound. It is, therefore, an object of the present invention to provide a nonslip surgical bandage that will not pull the skin of the user but will hold itself and the dressings or gauze in position.

Other surgical bandages have been proposed

2

which would eliminate the use of adhesive tape and would tend to resist any tendency to slip or shift; and those bandages were made of rubber or elastic fabric and would press against the patients' skin with appreciable force. Such bandages are not completely satisfactory because the material of which they are made is not acceptable to all persons, and, in addition it is more expensive than ordinary cloth. Furthermore, such bandages must be quite large to have sufficiently large area of contact with the skin of the user to prevent slipping or shifting; and, as a result, those bandages are unduly confining. In addition, the flexible material of those bandages overlies the dressings or gauze and can be stretched sufficiently to cause displacement or shifting of the dressings or gauze. Again this is objectionable since it may cause needless bleeding or may facilitate the onset of infection. For these reasons, surgical bandages which are made of rubber or elastic fabric are not satisfactory. The present invention obviates these objections by providing a nonslip surgical bandage that is largely made of ordinary cloth. It is therefore an object of the present invention to provide a nonslip surgical bandage that is largely made of cloth.

Surgical bandages should be capable of being used with patients of various sizes and shapes, and they should be usable with such patients without exerting undue pressures on any portions of the patients' bodies. Some surgical bandages have been proposed which could be adjusted to patients of different sizes and shapes, but those bandages either relied on the resiliency of the fastening means or the material adjacent thereto to provide adjustment, or they relied upon spaced buttons to selectively receive the fastening means and thus provide adjustment. The spaced buttons are objectionable because they must be located adjacent the incision or wound to provide proper application of pressure to the dressings or gauze; and when so located they can easily result in uncomfortable pressure points on the patient. The reliance on the resilience of the fastening means or the material adjacent thereto to facilitate adjustment is objectionable because that resilience may actually permit shifting or slipping of the dressings or gauze. For these reasons previously proposed surgical bandages are objectionable. The present invention obviates these objections by providing a cloth surgical bandage with loops adjacent the incision or wound that provide proper application of pressure without creating uncomfortable pressure

points on the patient, and it also provides yielding sections that are spaced away from the incision or wound. It is, therefore, an object of the present invention to provide a surgical bandage with loops adjacent the incision or wound and with yielding sections spaced away from the incision or wound.

In using an adjustable nonslip surgical bandage, it is often necessary to retain the bandage on the person of the user throughout the entire time the wound requires sterile dressings. This may be several days or even several weeks; and, of course, during that period the bodily functions of the patient must occur. While those bodily functions must be permitted to take place, they must not be permitted to interfere with the maintenance of the sterile condition of the dressings or gauze held by the surgical bandage. The present invention provides a bandage that makes this possible by providing a nonslip surgical bandage which extends around the trunk of the patient and has leg portions that extend along the outer surfaces of the legs and are held in place by ties which extend around the inside surfaces of the legs at points intermediate the knees and hips of the user. In this way the holding portions of the bandage are so located that the bodily functions of the user can be taken care of without necessitating the removal or shifting or soiling of the surgical bandage. It is, therefore, an object of the present invention to provide an improved surgical bandage which has a portion which extends around the trunk of the user and has leg portions that extend along the outside surfaces of the legs of the user and are held in place by ties which extend around the inside surfaces of the legs at points intermediate the knees and the hips of the user.

The surgical bandage of the present invention has its shortest girth at the top thereof, and it has an appreciably longer girth at its middle. Moreover, the bandage is so made that the top thereof can be adjusted to snugly fit the waist of the user. As a result, the very shape of the bandage cooperates with the shape of the user to resist slipping or shifting of the bandage downwardly; and since the leg portions of the bandage cooperate with the shape of the user's legs to resist upward slipping or shifting of the bandage, the bandage is always positively held against slipping or shifting. The top of the bandage and the leg portions are spaced apart an appreciable distance and, therefore, they will not exert undesirable pulling or pressure on the incision or wound.

Other objects and advantages of the present invention should become apparent from an examination of the drawing and accompanying description.

In the drawing and accompanying description, a preferred form of the invention is shown and described but it is to be understood that the drawing and accompanying description are for the purposes of illustration only and do not limit the invention and that the invention will be defined by the appended claims.

In the drawing, Fig. 1 is an elevational view of the outer surface of a surgical bandage embodying the principles and teachings of the present invention, and it shows that bandage as it is unfolded; and

Fig. 2 is a perspective view of the bandage of Fig. 1, as that bandage is folded in position around the body of a person, indicated by dotted lines.

Referring to the drawing in detail, the numeral 10 denotes the central portion of the bandage provided by the present invention and that portion of the bandage will normally engage the back of the patient's trunk. The central portion 10 has integrally formed, downwardly depending projections 12 which will extend along the outer surface of the legs of the patient and those downwardly depending projections are provided with straps or ties 14 which are sufficiently long to extend around the inner surfaces of the patient's legs. The top of the central portion is provided with darts 16 and those darts cooperate with the cut of the central portion 10 to enable the central portion 10 to have its shortest girth at the top thereof.

A number of short pieces of elastic material 18 are aligned in two spaced rows, and are securely and permanently attached, as by stitches, to the side edges of the central portion 10. The pieces of elastic material 18 are set close to each other but they are individually operable to expand or contract, thus facilitating the adjustment of the bandage to the person of the user.

Side portions 20 are securely and permanently attached, as by stitching, to the outer edges of the aligned elastic strips 18; and the portions 20 are thus securely and permanently attached to the central portion 10. The side portions 20 are provided with darts 22; and those darts 22 cooperate with the cut of the side portions 20 to enable the side portions 20 to have their shortest girths at the top. Since the elastic strips 18 have the same width, in relaxed condition, the bandage will, in its relaxed position, have its shortest girth at the top thereof.

The side portions 20 are provided with integrally formed, downwardly extending projections 24 that can also extend along the outer surfaces of the legs of the patient. The downwardly extending projections 24 are provided with loops 26 at the bottom of the outer edges thereof. These loops are made large enough to receive the straps or ties 14 without wrinkling or folding; and they hold the straps or ties 14 in position against the person of the user. The ends of the straps or ties 14 may be releasably attached to the downwardly projecting portions 24, as by safety pins 28.

The side portions 20 are also provided with a number of spaced pinning tabs 30; and these tabs are securely and permanently attached to the side portions 20 by having just one of their ends stitched to the side portions 20. The other ends 35 of the pinning tabs 30 are free, thus facilitating attachment of pins to the tabs without any danger of pricking the patient. In addition, the pinning tabs 30 also act to cushion the person of the user against pressure which contact between 60 the bed clothes and the pins might otherwise tend to exert. Spaced from, but in register with, the pinning tabs 30 are loops 32; and these loops are adjacent the outer edges of the side portions 20.

Formed integrally with the side portions 20 are spaced straps or ties 34 which project outwardly from the outer edges of the side portions 20. The straps or ties 34 on each side portion 20 alternate with the loops 32 on that side portion; 70 and the straps or ties 34 on one of the side portions 20 alternate with the straps or ties 34 on the other side portion 20. As a result, the straps or ties 34 supplement rather than duplicate each other; and they can operate, as shown in Fig. 2, 75 to provide a practically continuous supporting

surface which overlies the dressings or gauze. The straps or ties 34 of each side portion 20 will pass through the loops 32 and will be releasably pinned to the pinning tabs 30 of the other side portion 20. Safety pins 36 can be used to secure the straps or ties 34 to the pinning tabs 30.

The loops 32 provide very close control of the straps or ties 34 without making it necessary to place the safety pins 36 close to the incision or wound. In this way any pressure that may be developed by the bed clothing on the safety pins 36 will be developed at points spaced from the incision or wound; and thus the wound will be free from pressure points of this type.

The side portions 20 of the bandage are so dimensioned that, when the bandage is applied to the person of the user, the side portions 20 will not meet but will leave an open space; and this open space will be spanned by the straps or ties 34. The open space can be made larger or smaller than the space shown in Fig. 2 by using a larger or smaller bandage or by stretching or relaxing the elastic strips 18. In this way the size of the space can be made to fit the requirements of the dressing or gauze for the incision or wound. The width and number of the straps or ties 34 is such that when the straps or ties have passed through the loops 32 and have been pinned to the tabs 30, the straps or ties 34 form an almost continuous cover for the sterile dressings or gauze placed against the incision or wound.

The downwardly depending projections 12 of the central portion and the downwardly depending projections 24 of the side portions 20 are dimensioned so they cover only the outer surfaces of the user's legs, thus leaving the inner surfaces of the user's legs quite free and open. The straps or ties 14, which are attached to the downwardly depending projections 12 will extend around the inner surfaces of the user's legs but they are narrow and will not encumber the inner surface of the user's legs. The straps or ties 14 will be pinned or otherwise secured to the projections 24 of the side portions 20 and will cooperate with the projections 12 and 24 to limit upward movement of the bandage.

The bandage is so formed and dimensioned that the central portion 10 will extend across the back of the user's trunk, the elastic strips 18 will be located at the user's sides, the side portions 20 will extend over a part of the front of the user's trunk, and the straps or ties 34 will cover the rest of the front of the user's trunk. The short girth at the top of the bandage will enable the bandage to fit the waist of the user, and the wider girth at the middle of the bandage will enable the bandage to fit the hips of the user. These two girths will cooperate with the shape of the user to resist downward movement of the bandage, and the straps or ties 14 and the downwardly depending projections 12 and 24 will cooperate with the shape of the user's legs to resist upward movement of the bandage, thus enabling the bandage to avoid slipping or shifting.

The central portion 10 and the side portions 20 are also formed and dimensioned so the major portions thereof are above a line between the large trochanters of the femur bones of the user, thus providing ample room for attendance to bodily functions. In addition, by having most of the central and side portions of the bandage above that line, those portions do not have to accommodate the marked change of curvature adjacent that line and thus wrinkling of the cen-

tral and side portions of the bandage is avoided. The straps or ties 14 are spaced downwardly an appreciable distance from the line connecting the large trochanters, and thus they will not be soiled or stained.

The elasticity of the strips 18 and the adjustability of the straps or ties 34 permit the bandage to be used on patients of varying size and weight without any discomfort to the patient. In addition, the elasticity of the strips 18 permit free muscular movement of the legs and abdominal muscles without a shifting of the straps 34 relative to the incision or wound. Thus it is possible to place the sterile dressings or gauze directly over the incision or wound and affix the straps or ties 34 in position over the sterile dressings or gauze, and fully protect the patient against needless bleeding or infection caused by shifting or slipping of the dressing.

The bandage provided by the present invention is completely smooth on its inner surface, all of the loops and tabs being attached to its outer surface. As a result the bandage fits smoothly and comfortably against the person of the user. The bandage is further desirable because the straps or ties 34 do not overlap; as a result the bandage will not be wrinkled and will not be bulky. Furthermore, this permits each strap or tie to be handled individually, thus avoiding complicated lacing of the straps or ties. In addition, the edges of the straps or ties 14 and 34 are provided with stitching 15 and 35 respectively to prevent "rolling" of the straps or ties as a result of washing or repeated usage. Thus the bandage will always be easy to apply and will always provide smooth and uniform application of pressure to the sterile dressings or gauze.

Whereas a preferred embodiment of the present invention is shown and described in the drawing and accompanying description, it should be obvious to those skilled in the art that various changes may be made in the form of the invention without affecting the scope thereof.

What I claim is:

1. A bandage that comprises a central portion, a plurality of side portions that have free edges which are spaced apart to define an area adjacent an incision or wound, broad, flat outwardly extending ties on said side portions, said ties projecting outwardly from the free edges of said side portions, the ties on each of said free edges of said side portions being spaced apart distances approximating the width of the ties on the free edge of the opposed side portion, the ties on each of said free edges of said side portions being in register with the spaces between the ties on the free edge of the opposed side portion, pinning tabs on said side portions that are spaced inwardly from the free edges of said side portions, and tie-receiving loops adjacent the free edges of said side portions.

2. A surgical bandage that has a central portion which is adapted to extend across the back of a patient, a plurality of side portions which are dimensioned to extend around the sides of said patient and to define an open area coextensive with the abdomen of said patient, a plurality of individual elastic members aligned along both edges of said central portion and attaching said side portions to said central portion, a plurality of broad, flat ties that extend outwardly from the free edges of said side portions of the bandage and are adapted to overlie the said open area, the ties on the free edge of one of said side portions being spaced apart distances equal to

the width of the ties on the free edge of said other side portion and the ties on the free edge of said other side portion being spaced apart distances equal to the width of the ties on the free edge of said one side portion, the ties on the free edge of each of said side portions being in register with the spaces between the ties on the free edge of the opposed side portion whereby said ties on said side portions can coact to overlie sterile dressings or gauze applied to an incision or wound in the abdomen of the patient, leg portions which extend below the hips of the user and which have spaced, confronting edges, ties which extend between the said confronting edges of said leg portions at points intermediate the patient's hips and knees and hold the bandage against movement upwardly, said bandage being dimensioned so the top thereof is smaller than dimensions located downwardly from the top whereby the bandage can resist movement downwardly, pinning tabs spaced inwardly from the free edges of said side portions of the bandage, and loops adjacent the free edges of said side portions, said loops being adapted to receive the ties and to provide close control of the pinning of the bandage without necessitating the provision of pins adjacent the incision or wound.

3. A bandage that is adapted to hold dressings adjacent an incision or wound, said bandage having spaced free edges that define an area surrounding said incision or wound, ties that extend outwardly from said free edges of said bandage to overlie said area and said incision or wound, and tie-confining members adjacent said free edges of said bandage, said ties being adapted to span the space between said free edges, being adapted to be confined by said tie-confining members, and being adapted to extend beyond said tie-confining members and be secured to said bandage at points spaced from said tie-confining members, whereby securing devices that are used to secure said ties to said bandage are spaced from and cannot exert pressure on said incision or wound.

4. A bandage that is adapted to hold dressings adjacent an incision or wound, said bandage having spaced free edges that define an area surrounding said incision or wound, ties that extend outwardly from said free edges of said bandage to overlie said area and said incision or wound, tie-confining members adjacent said free edges of said bandage, said ties being adapted to span the space between said free edges, being adapted to be confined by said tie-confining members, and being adapted to extend beyond said tie-confining members and be secured to said bandage at points spaced from said tie-confining members, and pinning tabs on said bandage, said pinning tabs being said points spaced from said tie-confining members, whereby securing devices that are used to secure said ties to said pinning tabs are spaced from and cannot exert pressure on said incision or wound.

5. A bandage that is adapted to hold dressings adjacent an incision or wound, said bandage having spaced free edges that define an area surrounding said incision or wound, a plurality of broad, flat ties extending outwardly from one of said free edges to span the space between said free edges and thus overlie said area and said incision or wound, and tie-confining members adjacent the other of said free edges to confine

said ties, said ties being confined by but extending beyond said tie-confining members, whereby securing devices that are used to secure said ties to said bandage are spaced from and cannot exert pressure on said incision or wound.

6. A bandage that is adapted to hold dressings adjacent an incision or wound, said bandage having spaced free edges that define an area surrounding said incision or wound, a plurality of ties extending outwardly from said free edges to span the space between said free edges and to overlie part of the bandage beyond said free edges, said ties from one free edge alternating with the ties from the other free edge, and tie-confining members adjacent said free edges, said ties extending through and beyond said tie-confining members whereby securing elements that secure said ties to said bandage will be spaced from said incision or wound and cannot create a pressure on that incision or wound.

7. A bandage that is adapted to hold sterile dressings or gauze adjacent an incision or wound in the abdomen of a patient and that comprises a central portion of relatively elastic material that is adapted to extend across the back of the patient, a plurality of side portions of relatively inelastic material that extend around the sides of said patient, an elastic element extending between and connecting said central portion with one of said side portions, a second elastic element extending between and connecting said central portion with the other of said side portions, said central portion and said side portions and said elastic elements being dimensioned so said elastic elements are disposed adjacent the sides of said patient and are spaced from said incision or wound.

8. A bandage that is adapted to hold sterile dressings or gauze adjacent an incision or wound in the abdomen of a patient and that comprises a central portion of relatively inelastic material that is adapted to extend across the back of the patient, a plurality of side portions of relatively inelastic material that extend around the sides of said patient, a plurality of individual, aligned elastic elements extending between and connecting said central portion with one of said side portions, a second plurality of individual, aligned elastic elements extending between and connecting said central portion with the other of said side portions, said central portion and said side portions and said elastic elements being dimensioned so said elastic elements are disposed adjacent the sides of said patient and are spaced from said incision or wound, said individual, aligned elastic elements being individually extensible to varying extents to accommodate patients of varying size and weight.
